BREAKER ATTACHMENT

Edwin C. Gryce, Bemidji, Minn.

Application October 10, 1951, Serial No. 250,635

3 Claims. (Cl. 116—114)

1

My present invention relates to a novel breaker attachment for an equipment such as a drag line, a grapple and the like.

It is an object of this invention to provide a novel breaker means for embodiment in an equipment and having a predetermined tensile strength, whereby the breaker means will break apart by a stress greater than the tensile strength of the breaker means being applied to the same, and thus prevent damage or breakage to the equipment.

A further object of this invention is to provide a novel breaker means for embodiment in an equipment and having a predetermined tensile strength, whereby the breaker means will break apart by a stress greater than the tensile strength of the breaker means and give the operator a pre-warning of over-strain in the equipment to shut down the power before breakage in the equipment takes place, thus eliminating flying ends or parts of the equipment.

Other objects of the invention will be apparent from the following description, reference being had to the drawings.

To the above end, generally stated, the invention consists of the novel devices and combination of devices hereinafter described and defined in the claims.

In the accompanying drawings, which illustrate the invention, like characters indicate like parts throughout the several views.

Referring to the drawings:

Fig. 1 is a plan view, with a portion of the cover broken away, showing one embodiment of the invention;

Fig. 2 is a view corresponding to Fig. 1, with the exception that the cover is removed and some parts sectioned;

Figs. 3, 4, 5, 6 and 7 are views in transverse vertical section taken on the lines 3—3, 4—4, 5—5, 6—6 and 7—7 of Fig. 2;

Fig. 8 is a fragmentary plan view showing a different way of attaching the right-hand section of the cable to the housing;

Fig. 9 is a side elevational view of the parts shown in Fig. 8;

Fig. 10 is a plan view, with portions of the cover broken away, showing another embodiment of the invention;

Fig. 11 is a view corresponding to Fig. 10, with the exception that the cover and the compression caps are removed; and

Figs. 12 and 13 are views in transverse vertical section taken on the lines 11—11 and 12—12 of Fig. 11, respectively.

Referring first to the invention shown in Figs. 1

2

to 7, inclusive, the device is shown connecting two aligned sections 14 and 15 of a cable 16, as shown, a wire rope. This embodiment of the invention includes a closed housing 17, in the form of a rectangular, elongated box 18, and a cover 19 therefor in the form of a flat plate, detachably secured to said box by a plurality of cap screws 20. The right-hand end member 18^a of the box 18 is relatively thick and the left-hand end member 18^b thereof has on its outer side a boss 18^c.

The cable section 15 is attached to the right-hand end member 18^a of the box 18 by a butt or socket attachment. A deep, narrow channel 21 is formed in the end member 18^a and extends transversely of the box 18. The attachment of the cable section 15 to the box 18 includes an inwardly flaring annular or truncated conical socket 22. This socket 22 extends into the end member 18^a from the center of its outside to the channel 21. In the wall of the end member 18^a, surrounding the socket 22, is an annular groove 23. The inner end portion of the cable section 15 is inserted into the socket 22, the wires thereof in said socket spread apart and molten zinc poured into the socket 22, from the channel 21, to fill said socket and the groove 23 and the interstices between the spread wires of the cable section 15.

A slidable assembly 24 in the box 18 includes an outer slide member 25 and an inner slide member 26, each being in the form of an upright rectangular block that has a loose working fit with the interior of the box 18 and its cover 19. The assembly 24 is in the right end portion of the box 18 and its member 25 is between the slide member 26 and the end member 18^b. The two slide members 25 and 26 are connected by a pair of laterally spaced bolts 27 that extend loosely through holes in the slide member 25, have screw-threaded engagement with the slide member 26 and the heads 28 of said bolts are countersunk in the outer face of the slide member 25.

The inner end portion of the cable section 14 extends into the box 18 through a hole 29 in the center of the boss 18^c and the end member 18^b. This hole 29 flares outwardly to lessen the wear between the end member 18^b, the boss 18^c and the cable section 14. The cable section 14 is attached to the slide member 25 in the same manner that the cable section 15 is attached to the end member 18^a and the flaring socket and the annular groove of the present connection are designated by the numerals 30 and 31, respectively.

The slidable assembly 24 is attached to the longi-

50 55 box 18 by a breaker member 32 at the longi-

tudinal center of the housing 17. This breaker member 32 is elongated, round in cross-section and its end portions 33 are thickened by increasing the diameter thereof. On each end of the breaker member 32 is a large head 34. The breaker member may be made of any suitable material. A compression cap 35 is mounted in a recess 36, in the upper portion of the end member 18^a, between the channel 21 and the adjacent side of said end member, and is removably secured to the end member 18^a by a pair of cap screws 37. A pair of opposing half-seats 38 are formed in the end member 18^a at the bottom of the recess 36 and the under side of the compression cap 35. A second compression cap 39 is mounted in a recess 40 in the upper portion of the slide member 26 and detachably secured to said slide member by a pair of cap screws 41. A pair of opposing half-seats 42 is formed in the slide member 26, at the bottom of the recess 40, and the under side of the compression cap 39. Each compression cap 35-39 is in the form of a horizontal bar that extends transversely of the box 18.

As herebefore stated, the breaker member 32 connects the slidable assembly 24 to the housing 17 and this is accomplished by mounting the end portions 33 of said member in the pairs of half-seats 38-42 with one of the heads 34 of the breaker member 32 impinging the box end member 18^a and the compression cap 35, at the channel 21, as a base of resistance and the other head 34 impinging the inner side of the slide member 26 and the compression cap 39, as a base of resistance. Obviously, the compression caps 35-39 hold the end portions 33 of the breaker member 32 clamped in the half-seats 38-42. This mounting of the breaker member 32 leaves its intermediate portion between the end member 18^a and the assembly 24. This intermediate portion of the breaker member 32, which is of reduced diameter, has a tensile strength less than that of either cable section 14-15.

It will be understood that the breaker member 32 may take various different forms; for instance, it may be attached in the same manner as that shown in Figs. 10 to 13, inclusive. In this case, stronger cap screws would be necessary to hold the compression caps.

A cushion or shock absorber 43 in the box 18 is provided for the slidable assembly 24 in case it gave way due to a pulling strain that was greater than its tensile strength. This shock absorber 43, as shown, is a rectangular upright block of rubber placed against the end member 18^b as a base of resistance.

If the breaker member 32 gives way, the released assembly 24 will snap over against the shock absorber 43 and give the operator a pre-warning of overstrain on the cable 16 so that he can shut down the power and replace the breaker member 32. In this embodiment of the invention, there would not be any flying ends of the cable 16 when the breaker member 32 gives way, provided the operator would shut off the power before further breakage takes place.

Obviously, the "pre-shock" in the equipment produced by the release assembly 24 is ample warning to the operator that there is an overstrain on the equipment. While the breaker member 32 shown connects two sections of a cable, it will be understood that the same may be used to connect two members subject to a pulling strain. In other words, the breaker member 32 is intended for general use for the

purpose intended in connecting two members, but it is especially well adapted for use in connection with a drag line.

In Figs. 8 and 9 is shown a different way of attaching a cable to the box. In this instance, the box 18' has on its right-hand end an integral ring 44 and a thimble 45 interlocked therewith. The inner end portion of the cable section 15' is inserted through the ring 44, folded upon itself around the thimble 45 and the end portion thereof secured to the main portion of the cable section 15' by a wrapping of wire 46.

Referring now in detail to the invention shown in Figs. 10 to 13, inclusive, the numeral 47 indicates a housing comprising a rectangular elongated box 48 and a cover 49 therefor. The cover 49 is a flat plate secured by cap screws 50 to the box 47. The right-hand end of the box 48 is open and the left-hand end thereof is closed and integral therewith is a ring 51.

A slidable member 52 is held in the box 48 for sliding movement therefrom through the open end thereof, when released, as will presently appear. This slidable member 52, as shown, is a flat plate that rests on the bottom of the box 48 and has side flanges 53, the upper edges of which clear the under side of the cover 49. The front end of the slidable member 52, between the flanges 53, is closed as indicated at 54, and integral therewith is a ring 55 that projects outwardly of the box 48.

A base member 56 in the left-hand end portion of the box 18' is integral therewith and a similar base member 57 in the right-hand end portion of the slidable member 52 is integral therewith. A compression cap 58 is secured to the base member 56 by a pair of cap screws 59, and a like cap 60 is secured to the base member 57 by a pair of cap screws 61. The compression caps 58-60 are each in the form of a bar that extends transversely of the box 18' over the respective base members 56-57. A pair of opposing half-seats 62 are formed in the upper side of each base member 56-57 and the under side of the respective compression caps 58-60. The half-seats 62 of each pair are in the form of a truncated cone and flare outwardly.

A breaker member 63 connects the box 18' and the slidable member 52 and is made of any suitable material, preferably non-corrosive. This breaker member 63 is relatively long, round in cross-section, as shown, and the end portions thereof are in the form of truncated cones 64 that fit in the half-seats 62.

A fragment of a thimble 65 is interlocked with each ring 51-55 and a fragment of a section of a cable 66, as shown, a wire rope, is applied to each thimble 65. The breaker member 63 has a tensile strength less than the sections of the cable 66. When overstrain occurs on the cable 66 and the breaker member 63 is torn apart, the box 18' and the slidable member 52 are at the same time pulled apart, making a complete separation of the two sections of the cable 66.

The arrangement in Figs. 1 to 7, inclusive, is for partial or interrupted break, which is contrived to give the operator warning to hold up further strain when danger from breakage would need to be avoided.

The arrangement shown in Fig. 10 to Fig. 13, inclusive, is for full breaking apart of the two cable sections or other members, to be used in such cases where the release of a load cannot be prevented and in such cases when overload and breakage does not cause danger, for instance.

when a grappling hook could not be released from its hold. In such a case, the breaking member would be designed to be within the strength of the rigging and would let go. This structure is especially well adapted for use in connection with the drawbar pull of a tractor, which, if excessive, could and does upset the tractor with considerable loss of life.

While there are herein disclosed but a limited number of embodiments of the structure, process and product of the invention herein presented, it is possible to produce still other embodiments without departing from the inventive concept herein disclosed, and it is desired, therefore, that only such limitations be imposed on the appended claims as are stated herein, or required by the prior art.

What I claim is:

1. In a tackle to which a pulling strain may be applied, and breaker means holding the tackle to normally shorten its operative length without separating the same, said breaker means having a tensile strength less than that of the tackle, whereby the breaker means will pull apart when undue strain is applied to the tackle and permit the tackle to assume its greatest length by the pulling strain and thus produce a shock as a warning that the tackle is under undue strain.

2. A tackle to which a pulling strain may be applied, two interlocked members having a limited relative longitudinal movement, a cable attached to one of the members, means for attaching a load to the other member for holding the same, and breaker means holding the members retracted to shorten the operative length of the coupling, said breaker means having less ten-

sile strength than the tackle whereby the breaker means will pull apart when undue pulling strain is applied to the tackle and permit the pulling strain to pull the members into greatest length of the coupling and thus produce a shock as a warning that the tackle is under undue strain.

3. In a tackle to which a pulling strain may be applied, a coupling including a box-like body, a sliding assembly in one end position of said body comprising an inner block-like member and a similar outer member, means connecting said members, a cable extending into the opposite end of the body from the assembly through an aperture, and attached to the inner member, a breaker member connecting the outer members to the respective end of the body, means for attaching a load to the end of the body at the assembly, or for holding the same, said breaker means having less tensile strength than the tackle, whereby the breaker means will pull apart when undue pulling strain is applied to the tackle and permit the pulling strain to pull the assembly to the opposite end of the body and thus produce a shock as a warning that the tackle is under undue strain.
